UNITED STATES PATENT OFFICE.

FREDERICK LATULIP, OF SYRACUSE, NEW YORK, ASSIGNOR TO CHARLES S. NUTTING AND LUCY A. WILLIAMS, OF SAME PLACE.

SPRING.

SPECIFICATION forming part of Letters Patent No. 397,989, dated February 19, 1889.

Application filed June 7, 1888. Serial No. 276,406. (No model.)

To all whom it may concern:

Be it known that I, FREDERICK LATULIP, of Syracuse, in the county of Onondaga and State of New York, have invented certain new and 5 useful Improvements in Springs; and I do hereby declare that the following is a full, clear, and exact description of the invention, which will enable others skilled in the art to which it appertains to make and use the 10 same, reference being had to the accompanying drawings, and to the letters of reference marked thereon, which form part of this specification.

My invention relates to an improvement in 15 rocker-springs, and more particularly as an improvement on the spring set forth and claimed in Patent No. 355,769, granted to me January 1, 1887. Heretofore rocker-springs of this class have been formed in the shape 20 of an **S**, with the opposite ends of the spring rolled back upon themselves to form horizontal eyes falling in the same plane with the body of the spring, the spring being secured in position by screws or the like passed through 25 said eyes. This old manner of fastening the springs is subject to great difficulties and objections. The screws or nails employed have to be exceedingly long, and hence the strength 30 of the fastening is greatly impaired, as said screws or nails are liable to become broken or bent, and as but one eye can be formed at each end of the spring but one screw or nail can be employed to fasten an end. The inner edges of this form of spring are apt to 35 bear and rub against the surfaces to which they are secured when the rockers are operated, and hence wear the same and create unpleasant noises, and it is difficult to bend or roll the metal to form the eyes. It has also 40 been customary to secure **S**-shaped springs at their opposite ends to a rocker and a base by means of brackets secured, respectively, to the rocker and base and provided with laterally-extending lugs, to which the ends of 45 the spring are secured; but this mode of fastening is expensive and requires an excessive number of parts when compared with the device herein shown.

The object of my invention is to provide an 50 improved spring which shall be exceedingly cheap and simple in construction and over-

come the objections to the springs of this class heretofore in use, and which shall be especially adapted for connecting the rockers of chairs, cradles, or the like to the stationary 55 bases supporting the same.

With these ends in view my invention consists of a spring composed of a continuous spring metal bar curved in the shape of an **S**, and having its opposite ends turned at right 60 angles on the same side of the bar and bent laterally into a plane beyond the edge of the bar, each turned end being provided with one or more transverse apertures, whereby the spring is secured to the rockers and base, and 65 the body of the spring is kept away from the same without the necessity of using brackets or the like for this purpose.

Referring to the accompanying drawings, Figure 1 is a vertical transverse sectional view 70 showing the attachment of the spring to a rocker and its stationary support or base. Fig. 2 is a plan view of the same, and Fig. 3 is a detail plan view of the spring.

In the drawings, the reference-letter A in- 75 dicates the stationary base of a rocking-chair, cradle, or the like, and B denotes the rockers mounted on said base.

C indicates my improved spring, consisting, essentially, of spring metal loops *ll*, standing 80 in vertical planes and connected at opposite ends, respectively, with the base and rocker. To embody this feature in its simplest form, I construct said spring of a continuous bar of steel or other suitable spring metal, bent at 85 its central or main portion into the shape of an **S** and curved reversely at opposite ends in a uniform plane, said end portions forming the loops *ll*. The extreme ends *e e'* of the spring are bent laterally and turned at 90 right angles, so that their flat sides will be in planes at right angles to the planes of the similar sides of the main portion of the spring, and each of said turned and laterally-bent ends *e e'* is provided with one or more apertures, *f*, whereby the spring can be secured in position by screws or other means. The turned ends *e e'* are located on opposite sides of and preferably in proximity to the central portion of the bar, and are bent laterally upon the 100 same side of the spring a suitable amount, so that when the ends are secured to the rock-

ers and base, respectively, with their flat faces bearing against the same, the inner edge of the spring will be held a suitable distance from the sides of the rockers and base, and thus all friction between the same will be avoided and a great difficulty heretofore experienced overcome. The bent end *e* of the spring attached to the rocker can be fastened by a single screw or bolt; but the bent end *e'*, attached to the base, is preferably longer than the opposite turned end *e*, and provided with two or more apertures, whereby two or more screws or bolts can be employed to secure said end to the stationary base where the most strain occurs.

What I claim is—

The herein-described spring, composed of a

continuous spring metal bar curved in the shape of an **S**, and having its opposite ends turned at right angles on the same side of the bar and bent laterally into a plane beyond the edge of the bar, each turned end being provided with one or more transverse apertures, as set forth.

In testimony that I claim the foregoing as my own I affix my signature in presence of two witnesses.

^{his}
FREDERICK X LATULIP.
